UNITED STATES PATENT OFFICE.

WALTER E. HOSCH, OF ST. LOUIS, MISSOURI.

TRACTION-WHEEL.

14,340.

Specification of Reissued Letters Patent. Reissued Aug. 7, 1917.

Original No. 1,191,898, dated July 18, 1916, Serial No. 21,754, filed April 16, 1915. Application for reissue filed October 9, 1916. Serial No. 124,727.

To all whom it may concern:

Be it known that I, WALTER E. HOSCH, a citizen of the United States, residing in the city of St. Louis, State of Missouri, have 5 invented a new and useful Improvement in Traction-Wheels, of which the following is a specification.

My invention relates to traction wheels of the type generally used on heavy vehicles, 10 such as tractors, motor vehicles, artillery, and heavy farming implements, such as threshing machines, motor plows, and the like, the principal object of my invention being to provide a comparatively light, 15 strong and durable wheel having its rim portion formed so as to provide a maximum degree of tractive effect between the tread surfaces of the wheel and the surface of the ground upon which the wheel travels, 20 and said rim portion being formed so as to engage and grip the surface of the ground, and reducing to a minimum the tendency of the wheel to slip or skid on slippery surfaces or to spin when soft ground is 25 encountered.

Further objects of my invention are, to provide a traction wheel having a rim portion made up of a series of segmental members, any one of which can be readily removed in case it becomes broken or unfit for service; to provide the sectional rim members with prongs or projections which engage in the ground over which the wheel passes, thereby producing the desired tractive effect between said wheel and the ground; to provide a detachable sectional member which is adapted to be applied to the rim of the wheel when the same is traveling on a roadway or pavement, which detachable member prevents the projections on the rim from entering or breaking through the surface of the roadway, and further to provide a wheel having a rim portion which is practically self-cleaning, inasmuch as said 35 rim portion is provided with openings through which soft dirt or mud will readily pass without clogging the spaces between the projections on the sections of said rim.

With the foregoing and other objects in 40 view, my invention consists in certain novel features of construction, and arrangements

of parts, hereinafter more fully described, claimed and shown in the accompanying drawings, in which—

Figure 1 is a side elevational view of a 55 traction wheel of my improved construction,

Fig. 2 is a bottom plan of a portion of the wheel rim upon an enlarged scale,

Fig. 3, is a plan view looking toward 60 the inner face of one of the rim sections,

Fig. 4 is a sectional view taken through a portion of the rim of my improved wheel about on the line 4—4 of Fig. 2,

Fig. 5 is a sectional view taken centrally 65 through a portion of the rim of the wheel and showing the removable tread member in position upon the rim,

Fig. 6 is an enlarged cross sectional view 70 of the rim portion of the form of wheel illustrated in Fig. 5,

Fig. 7 is a detailed view of a modified 75 form of the joint between the end portions of the sections of the removable tread member.

As illustrated in the drawings, the main body of my improved wheel comprises a hub 10, two sets of spokes 11, the members of which are arranged in pairs with their inner ends fixed in any suitable manner to 80 the end portions of the hub, and secured to the outer ends of each set of spokes is a rim member 12 in the form of a metal ring.

The rim or tread portion of my improved 85 wheel is supported by and occupies the space between the rings 12, and said rim portion is sectional in construction inasmuch as it is composed of a series of separately formed members which are alike in size and construction. Each member comprises a pair of side plates 13 which are curved to correspond with the curvature of the rings 12, and said plates are positioned directly against and rigidly fixed to said rings 12 90 in any suitable manner, preferably by means of rivets 14.

Formed integral with the outer portions of the plates 13 are outwardly projecting flanges 15 which bear directly against the outer edges of the rings 12. The plates 13 100 are provided with notches 16 or cut-away portions, which accommodate the outer ends

of the spokes 11, the same being rigidly fixed to the rings 12 in any suitable manner, preferably by means of rivets 14^a.

When the members forming the sectional rim are properly assembled, the ends of the plates 13 of one member abut and bear directly against the ends of the next adjacent members, and by virtue of such construction any abnormal strain upon one of the sections during service will be transmitted to the adjacent sections and this greatly distributes and reduces the shearing strain on the rivets. Each pair of plates 13 is connected at one end by a transversely disposed plate 17, the main body portion of which lies on the periphery of the wheel and occupies the same plane with the flanges 15; the outer face of each body portion forms a bearing face, and said body portion between said flanges projects rearwardly of the plates 13 with respect to the direction of rotation of the wheel, being provided with a curved back edge 18. Referring to Figs. 2 and 4 the forwardly disposed face 17^a of this plate 17 is curved or inclined upwardly with respect to the plane occupied by the main body portion of said plate, that is to say, inwardly toward the central axis of rotation of the wheel, and the curved forward edge 19 of said upwardly projecting forward portion occupies substantially the same plane with the inner edges of the plates 13. Thus, when the tractor members are properly assembled, there will be an opening formed between each pair of members, which opening readily permits soft earth, sand or mud to pass upwardly through the rim portion of the wheel, thereby practically eliminating the tendency of soft earth and the like to clog and pack on the tread portion of the wheel.

The forward portion of each tractor member has oppositely disposed inclined tread faces 19^a, inclined to the middle plane of the tractor, and which extend inwardly from the outer side portions toward the middle plane of the tractor, (see Fig. 2), and converge symmetrically toward each other in a rearward direction with respect to the direction of rotation of the wheel. In other words, the edges of the tread faces constitute the forward edge 19 of the tractor, and produce a reentrant edge, so that a curved pocket or contracted throat 19^b is formed in the middle plane of the tractor member where the tread faces 19^a unite. From the edge 19 the surface of the plate curves outwardly and merges into the outer face 19^c of the plate, which lies substantially on the circumferential line of the wheel. These tread faces compress the soil between them and give the wheel a high tractive effect. The contracted throat 19^b is open at its inner side so that at the forward edges of 65 the tread faces no obstruction is offered to

the earth passing through the throat. The tractor members may have other features that augment the tractive effect, as follows:—

Formed integral with the plate 17 at 70 points a short distance to each side of the transverse center thereof are outwardly projecting studs or projections 20, the same being preferably conical in shape, and formed integral with and projecting outwardly from 75 the end portions of said transverse plate are conical studs or projections 21. These studs or projections are arranged on the plate 17 so that portions of their surfaces coalesce or 80 blend with portions of the curved or inclined surface 17^a, and by virtue of such construction, when the wheel is traveling over soft or muddy ground, that portion thereof which is positioned in the space between the 85 projections will be forced upward along the inclined faces of said projections, and likewise, upward beneath the curved or inclined face 17^a. In other words, when the wheel is traversing soft or muddy ground, the engaged portion of the latter will be forced 90 upward and packed into compact masses within the pockets formed in the openings between the tractor members, and as a result, the tractor members are firmly supported and at the same time, the packed masses of 95 earth form a substantial base against which the projections engage to produce an increased or augmented tractive effect.

When a vehicle equipped with my improved wheel is traveling upon a pavement 100 or made roadway, it is desirable that the projections on the rim of the wheel be prevented from engaging in the surface of the roadway as such action would break and destroy the smooth finished surface, and to 105 overcome this, I have provided a guard or tread member which is adapted to be easily and quickly applied to or detached from the wheel. This tread member comprises a series of curved channel-shaped sections, 22, 110 each being of sufficient length to overlie a series of the tractor members, and when applied for use, said tread members lie between the studs or projections 20 as seen in Fig. 6. By reason of the fact that these 115 studs or projections are tapered toward their outer ends, the tread member 22 is necessarily widest at its outer face and said outer face occupies the same plane and lies flush with the outer ends of all of the studs 120 or projections. Thus, as the wheel passes over the pavement or made roadway, the outer faces of the sections 22 form the tread or engaging surface of the wheel and the studs or projections are prevented from 125 breaking through the surface of the roadway. The ends of the sections 22 are provided with inwardly projecting lugs 23, the same extending between pairs of the sectional rim members, and passing through 130

said lugs 23 are draw-bolts 24, which, when tightened, draw the tread sections firmly into position between the pairs of studs 20.

In Fig. 7 I have shown a modified form 8 of connection between the ends of the tread members 22, and in this modified construction, one end of one of the channel-shaped members is provided with a projecting tongue 25, in which is formed a notch 26, 10 and the end of the next adjacent section is provided with a transversely disposed pin 27 which, when the sections are properly assembled, engages in said notch 26.

A wheel of my improved construction 15 is comparatively simple, can be advantageously used upon all forms of vehicles, and particularly those designed for carrying heavy loads, and the construction of the rim portion of the wheel prevents the same 20 from slipping or skidding upon slippery surfaces, and likewise prevents the wheels from spinning when soft ground is encountered. Inasmuch as the rim portion of the wheel is of sectional construction or 25 made up of a series of segmental members, any one of said members can be readily removed in case it becomes broken or unfit for service. The removable tread member is easily and quickly applied to or removed 30 from the wheel, and provides simple means for preventing the studs or projections on the rim of the wheel from entering the surface of the pavement or a made roadway when the wheel is passing thereover.

35 It is evident that on account of the re-entrant form of the forward edges of the tractor members, the openings 19^a which are formed between each pair of adjacent tractor members have their greatest width 40 disposed forwardly with respect to the direction of rotation of the wheel and consequently just as each tractor member rises from the ground line, the earth lying in the widest portion of the opening tends to 45 fall to the earth and carry with it the earth which has become compressed in the contracted throat 19^b. In this way the tractor members tend to clear themselves of earth as the wheel rotates.

50 It will be readily understood that minor changes in the size, form and construction of the various parts of my improved traction wheel can be made and substituted for those herein shown and described, without 55 departing from the spirit of my invention, the scope of which is set forth in the appended claims.

I claim:

1. A traction wheel rim comprising a pair 60 of spaced supports and a series of rim sections secured to said supports, each of which sections comprises a transversely disposed plate, studs projecting outwardly therefrom, and a pair of side plates, which 65 latter are fixed to the spaced supports with

their ends bearing directly against the ends of the side plates of the adjacent rim sections.

2. A traction wheel rim comprising a pair of spaced supports and a series of rim sections secured to said supports, each of which sections comprises a plate, one edge of which is inclined with respect to the opposite edge, a series of studs formed on said plate, and a pair of side plates which are 75 secured to the spaced supports with their ends bearing directly against the ends of the side plates of the adjacent rim sections.

3. A traction wheel rim comprising a pair of spaced supports and a series of rim sections secured to said supports, each of which comprises a plate, one edge of which is curved inwardly with respect to the other edge, a series of studs projecting outwardly from said plate, and a pair of side plates 85 which are secured to the spaced supports with their ends bearing directly against the ends of the side plates of the adjacent rim sections.

4. The combination with a pair of spaced 90 supporting rings, of tread members positioned between said spaced rings, each of which members comprises a pair of side plates, the ends of which bear directly against the ends of the adjacent members, a 95 plate integral with said side plates, which plate is curved transversely, and a series of studs integral with and projecting outwardly from said plate.

5. The combination with a pair of spaced 100 supporting rings, of tread members positioned between and fixed to said rings, each of which members comprises a pair of side plates, the ends of which bear directly against the ends of the plates of the adjacent 105 tread members, a transversely disposed plate integral with said side plates, a series of studs projecting outwardly from said transversely disposed plate, and flanges on said side plates which bear directly against 110 the outer edges of the supporting rings.

6. In a traction wheel, the combination 115 with a pair of spaced supporting rings, of a series of tread sections arranged between and fixed to said rings, a series of studs projecting outwardly from the tread surfaces of each section, each series of studs being arranged in a transversely disposed curved row.

7. In a traction wheel, the combination 120 with a pair of spaced supporting rings, of a series of tread sections arranged between and fixed to said rings, a series of studs projecting outwardly from the tread surfaces of each section, each series of studs being arranged in a transversely disposed curved 125 row, and there being openings formed between said tread members.

8. The combination with a traction wheel 130 rim having outwardly projecting studs on

its tread surface, of a sectional tread member applied to the outer face of the rim and positioned between the studs thereon, the sections of which tread member are substantially channel-shaped in cross section, and readily detachable means for securing the ends of the tread members to each other.

9. The combination with a traction wheel rim having outwardly projecting studs on 10 its tread surface, said studs being arranged in circumferentially disposed rows, of a sectional tread member applied to the outer face of the rim and positioned between the central pair of circumferentially disposed rows of studs.

10. The combination with a traction wheel rim, having outwardly projecting studs on its tread surface, said studs being arranged in circumferentially disposed rows, of a 20 sectional tread member applied to the outer face of the rim and positioned between the central pair of circumferentially disposed rows of studs, and readily detachable means for securing the ends of the tread members 25 to each other.

11. A tractor member consisting of a plate to be attached to the rim of a tractor wheel, said plate having a reentrant edge on the forward side of the plate with respect 30 to the direction of rotation of the wheel, the middle portion of said reentrant edge extending rearwardly to form a contracted throat in the middle plane of the wheel, said plate having a body portion disposed outwardly, and having inclined tread faces projecting inwardly from the plane of said body portion and extending along said reentrant edge.

12. A tractor member constructed to be 40 attached at the rim of a tractor wheel, having a body portion disposed outwardly, and having oppositely disposed inclined tread faces for engaging the earth extending inwardly from said body portion, the forward 45 edges of said tread faces, with respect to the direction of rotation, constituting the forward edge of said tractor and extending inwardly toward the middle axis of the tractor member from the outer portion thereof and converging toward each other rearwardly so as to form a contracted throat 50 projecting rearwardly in the middle plane of said tractor member, said throat being open at its inner side so as to permit the earth in the middle plane of the wheel to 55 pass freely through the throat.

13. A tractor member having a body formed of a plate to be attached to the rim 60 of a tractor wheel, said plate having a reentrant edge on the forward side of the plate with respect to the direction of rotation of the wheel, said edge being located inwardly so as to be toward the axis of the wheel, said plate having an outer face to lie

at the circumference of the wheel, and having a curved face extending outwardly from said edge and merging into said outer face.

14. A tractor wheel having a plurality of tractor members attached thereto, each of 70 said tractor members consisting of a plate having a reentrant edge on the forward side of the plate with respect to the direction of rotation of the wheel, the middle portion of said reentrant edge extending rearwardly to form a contracted throat in the middle plane 75 of the wheel, each of said plates having a body portion lying substantially on the periphery of the wheel and having an inclined tread face projecting inwardly from said body portion toward the wheel center and 80 extending along said reentrant edge, said tractor members being disposed adjacent to each other on the rim of the wheel, and said throats being unobstructed whereby the earth under compression may pass freely 85 through said throats.

15. A tractor wheel comprising a wheel having a plurality of tractor members disposed around the circumference of the wheel so as to form openings through the face of 90 the wheel between the tractor members, each of said tractor members consisting of a transversely disposed plate having an outer portion disposed substantially on the circumferential line of said wheel, the said 95 outer portion having an inwardly disposed extension extending in a curved line transversely of the wheel, said curved line, toward the middle plane of the wheel, extending rearwardly with respect to the direction 100 of rotation of the wheel, said inwardly curved portion operating to compress the soil engaged thereby.

16. A tractor wheel comprising a wheel having a plurality of tractor members disposed around the circumference of the wheel so as to form openings through the face of the wheel between the tractor members, each of said tractor members consisting of a transversely disposed plate having an outer portion disposed substantially on the circumferential line of said wheel, the said outer portion having an inwardly disposed extension extending in a curved line transversely of the wheel, said curved line, toward the central plane of the wheel, extending rearwardly with respect to the direction of rotation of the wheel, said inwardly curved portion operating to compress the 110 soil engaged thereby, said plates each having a plurality of outwardly projecting studs for engaging the earth.

17. A tractor wheel having a plurality of tractor members attached on the rim thereof, 125 said tractor members each consisting of a plate having a body portion with its outer face disposed substantially on the periphery of the wheel, and having tread faces extend-

ing inwardly from said body portion toward the wheel center, the forward edges of said tread faces converging toward the middle plane of the wheel and in a rearward direction with respect to the direction of rotation, said tractor members being disposed adjacent to each other whereby openings are formed therebetween, said wheel constructed so as to support said tractor members at the sides thereof and leave the said openings unobstructed in the middle plane of the wheel.

18. A tractor wheel having a plurality of tractor members attached on the rim thereof, said tractor members each consisting of a plate having a body portion with its outer face disposed substantially on the periphery of the wheel, and having curved tread faces constituting continuations of the outer faces of said plate, and extending inwardly, the forward edges of said tread faces converging toward the middle plane of the wheel and in a rearward direction with respect to the direction of rotation, said tractor members being disposed adjacent to each other whereby openings are formed therebetween, said wheel constructed so as to support said tractor members at the sides thereof and leave the said openings unobstructed in the middle plane of the wheel.

19. A tractor wheel having a plurality of tractor members at the rim thereof, each

tractor member having tread faces for engaging the earth, said tread faces extending inwardly from the outer portions of the said tractor members toward the middle plane thereof, and converging toward the central axis of the wheel, said tractor members being disposed apart so that openings are formed at the rim of the wheel between the adjacent tractor members, said openings lying in the middle plane of the wheel.

20. A tractor wheel having a plurality of tractor members with tread faces for engaging the earth, said tread faces extending inwardly from the outer portions of the tractor members toward the middle plane thereof, said tread faces each having a forwardly disposed reentrant edge whereby a contracted pocket is formed on the forward edge of each tractor, in which the earth is compressed, said tractors being disposed apart so that an opening is formed between each pair of adjacent tractors, each of said openings having its greatest width forward with respect to the direction of rotation of the wheel, whereby as the tractors leave the ground the weight of earth in the widest part of each opening tends to gravitate to the ground and dislodge with it the compressed earth lying in the said pockets.

Signed at St. Louis, in the State of Missouri, this 4th day of October, 1916.
